United States Patent Office.

DARIUS C. BROWN, OF LOWELL, MASSACHUSETTS.

Letters Patent No. 72,967, dated January 7, 1868.

IMPROVEMENT IN HARNESS FOR LOOMS.

The Schedule referred to in these Letters Patent and making part of the same.

TO ALL WHOM IT MAY CONCERN:

Be it known that I, DARIUS C. BROWN, of Lowell, Middlesex county, Massachusetts, have invented a new and useful "Improvement in the Hanging of Heddles for Looms;" and I do hereby declare that the following is a full, clear, and exact description thereof, which will enable others skilled in the art to make and use the same, reference being had to the accompanying drawings, forming part of this specification.

This invention relates to the hanging of the heddles in and to their frame; and it consists in hanging the series of heddles at one end, which I prefer should be the upper, upon a common rod or bar of the heddle-frame, but at their opposite or lower end, alternately, and in regular order, upon two bars or rods secured in and to the frame, in planes parallel to and a short distance from each other, whereby, in the same width of heddle-frames, not only more heddles can be hung than when hung in the ordinary manner—an advantage of much importance—but insures the perfect drawing off of the heddles by the drawer or operator, to form the lease. In the accompanying plate of drawings my improvement in heddles for looms is illustrated—

Figure 1 being a front view of a heddle-frame, having its heddles hung in it according to the present invention, and

Figure 2 a transverse vertical section taken in the plane of the line x x , fig. 1.

Similar letters of reference indicate corresponding parts.

A, in the drawings, represents the heddle-frame, and B its heddles, the number of which may be more or less, as may be desired. These heddles, B, are hung at their upper ends to a common rod or bar, C, secured in the upper end of the heddle-frame, but at their lower ends are alternately hung, in regular order and succession, to and upon two parallel bars D, secured in such end of the heddle-frame; these bars being placed at a short distance from each other, and the one back of the other.

By hanging the heddles in the manner above explained, it is plainly obvious that a great amount of space or room is given to the heddle-eyes, thus enabling a larger number of them to be used than by the old method of hanging, and that, furthermore, the perfect drawing of the heddles for forming the lease is insured, as, if a wrong heddle is taken in hand by the drawer, it is stopped by the one before it, owing to its being hung upon a different bar or rod at its lower end.

I claim as new, and desire to secure by Letters Patent—

Hanging the heddles in their frame at one end to a common bar, but at their opposite ends to two or more bars, substantially as and for the purpose described.

D. C. BROWN.
